UNITED STATES PATENT OFFICE.

JESSE ALEXANDER, OF BROOKLYN, NEW YORK, ASSIGNOR, BY MESNE ASSIGNMENTS,
OF ONE-HALF TO EMMA SCHEU SCHORCHT, OF BUFFALO, NEW YORK.

TYPE-WRITER-CARRIAGE-FEEDING MECHANISM.

974,332.

Specification of Letters Patent.

Patented Nov. 1, 1910.

Continuation of application Serial No. 221,925, filed October 24, 1904. This application filed October 8, 1908
Serial No. 456,805.

To all whom it may concern:

Be it known that I, JESSE ALEXANDER, citizen of the United States, residing at Brooklyn, county of Kings, State of New York, have invented certain new and useful Improvements in Type-Writer-Carriage-Feeding Mechanism, of which the following is a full, clear, and exact description.

My invention relates to improvements in type-writers and particularly to the carriage-feeding mechanism therefor.

This application is a continuation of applicant's prior abandoned case Serial No. 221,925, filed October 24, 1904.

The object of this invention is to provide improved means for applying tension to the carriage of a machine to move it from one side to the other and at the same time provide escapement mechanism of such a character that the pressure upon the escapement-wheel which normally has the greatest amount of wear shall be much less than the tension on the carriage. This is effected by improvements the principles of which are illustrated in the accompanying two sheets of drawings.

Figure 1 is a plan view of such parts of a machine as are necessary for the illustration of this invention, parts being broken away. Fig. 2 is a detail rear view. Fig. 3 is a side elevation and section of parts shown in Fig. 1 taken on the plane of the lines $\alpha-\alpha$. Fig. 4 is a section and side elevation showing the tension device and system of reducing gears. Fig. 5 is a cross-section of the tension device. Fig. 6 is a detail showing the pawl and part of the tension device.

1 indicates the main frame of the machine. 2 is the back-plate affording a rear support for the carriage.

3 is a front guide-track for the carriage construction.

4 and 5 are side-plates of the carriage.

6 is a bar connecting the side-plates at the rear.

7 is a guide-block adapted to slide in a suitable guide in the back-plate 2.

8 is a thumb-screw for removably securing the back-bar 6 to the guide-block 7.

9 indicates rollers carried by the guide-block which are adapted to travel on the back-plate.

10 is a bar connecting the side-plates 4 and 5 near the front.

11 is a roller carried by the bar 10 and 55 guided in a slot in the front-track 3.

12 indicates a platen-shaft.

The general construction is more clearly shown, described and claimed in an accompanying application No. 456,806, filed October 8th, 1908.

13 is a block affording a bearing for the tension shaft 14.

15 is a drum which is pivotally mounted with relation to the shaft.

16 is a spring having one end secured to the drum 15 and the other end secured to the shaft 14.

17 is a ratchet connected with the drum 15 and preferably formed integral therewith.

18 is a double-acting pawl which is pivotally carried by the frame of the machine and adapted to coact with the ratchet 17 to hold it in position as indicated in Fig. 6. The normal tension of the spring will rotate the shaft 14 clockwise as viewed from the rear.

19 is a second drum which is secured to the shaft 14 and rotates therewith.

20 is the tension or pull-strap which is secured at one end to the drum 19 and at the other end to the projecting arm 21 carried by the guide-block 7. Whenever the shaft 14 is free to rotate the carriage will be moved to the left. Normally, however, the shaft 14 is restrained by the escapement mechanism and the reducing gears.

22 is a typebar-plate affording a bearing for the type-bar 23.

24 is the universal-bar mounted at the rear of the type-bar plate 22 and adapted to be operated by the type bars.

25 is the universal-shaft.

26 is a projection from the rear of the universal-bar 24 connected to the arm 27 which is carried by the universal-shaft 25.

28 is a universal-arm carried by the shaft 25.

29 is a shaft pivoted in the carriage side-plates 4 and 5 and carrying the stop-bar 30.

31 is an arm for manually releasing the stop-bar from its operative position.

32 is a suitable spring for holding the stop-bar in position.

33 is a ratchet-wheel carried by the shaft 34. This ratchet engages with the bevel edge of the stop-bar 30 as shown particularly in Figs. 2 and 3. This ratchet is connected by a train of gears to the tension shaft 14. This train consists of a pinion 35, wheel 36, bevel gears 37 and 38, the latter of which is mounted on the shaft 14.

From the foregoing, it will be seen that 10 when the parts are in the position shown in the drawings, the tension of the spring 16 is resisted by the pressure of the ratchet against the stop-bar 30. There is, therefore, no operative tension exerted upon the pull-15 strap 20. When, however, the universal-arm 28 is moved to the rear, by its action through shaft 25, arm 27 and projection 26 to the universal bar 24, when a type-bar 23 is operated and moves the universal bar 27 20 by engagement therewith, its upper end 40 which is beveled engages the stop-bar 30 and tilts the same slightly so as to release the ratchet 33. At the same time, the pin 41, which is carried by the bevel-arm 28, is interposed in front of the next approaching 25 tooth of the ratchet, so that when the universal-arm 28 is released the ratchet will have advanced one tooth. This permits the tension-shaft 14 to rotate and thus a pull is 30 exerted upon the band 20 and the carriage moved to the left.

In order that the carriage may move uniformly the same distance each time the escapement mechanism operates, I have provided the retarding mechanism. 42 is a toothed-plate carried by the stop-bar 30. 43 is a dog pivoted to the frame of the machine. 44 is a spring for holding it in the position shown in Fig. 2. When the stop-bar 40 is in its normal position, the carriage cannot be moved to the left, except by the release of the stop-bar 30. This release is accomplished of course either manually by the handle 31 or by the universal mechanism. 45 In the latter case, the universal-arm 28 allows the stop-bar 30 to descend and thus cause the toothed-plate 42 to engage the pawl 43 and stop the carriage. The carriage may be moved to the right merely by manually 50 releasing the stop-bar 30, or it may be moved to the right without releasing the stop-bar since I have provided a ratchet connection between the tension-shaft 14 and the bevel-gear 38. This consists of a spring-pawl 44 carried by the tension-shaft and the ratchet 45 carried by the bevel-gear 38. This permits the tension-shaft 14 to rotate in the opposite direction to the arrows as shown in Fig. 1 without rotating the gears. 55 60 By this construction it is possible to exert a strong pull upon the carriage when it is desired to move the carriage step by step but when at rest there is practically no longitudinal tension on the carriage. This re-

duces the wear of the parts of the escapement mechanism in a longitudinal direction and consequently reduces the error of alignment which would be caused thereby.

The advantages of this will be apparent to those skilled in the art.

What I claim is—

1. A typewriter carriage feeding mechanism, including a carriage construction, a tension device connected to the carriage, a universal bar, a pivoted stop bar provided with a series of teeth, means coöperating with said stop bar for normally preventing said tension device from exerting a pull on said carriage, escapement means operated by said universal bar for permitting said tension device to operate, and a spring-pressed pawl for overcoming the momentum of the carriage when said tension device is checked by engaging the teeth on the stop bar.

2. A typewriter carriage feeding mechanism, including a carriage construction, a tension device connected to the carriage, a universal bar, a stop bar movably carried by said carriage, a ratchet coöperating with said stop bar, means of connection between said tension device and said ratchet, said carriage normally being under no longitudinal tension, a member carried by the universal bar coöperating with the stop bar to form an escapement for said ratchet, and means for operating said escapement mechanism for permitting said tension device to move said carriage.

3. A typewriter carriage feeding mechanism, including a carriage construction, a tension device connected to the carriage, a universal bar, a stop bar movably carried by the carriage, a ratchet coöperating with said stop bar, means of connection between said tension device and said ratchet, said carriage normally being under no longitudinal tension, a member carried by the universal bar coöperating with said stop bar to form an escapement for said ratchet, means for operating said escapement mechanism for permitting said tension device to move said carriage, and means for checking the momentum of said carriage.

4. A typewriter carriage feeding mechanism, including a carriage construction, a tension device connected to the carriage, a universal bar, a stop bar carried by said carriage, a ratchet coöperating with said stop bar, a train of gears connecting said tension device and said ratchet, said tension device normally tending to rotate said ratchet and the member on said universal bar coöperating with the stop bar to provide an escapement mechanism for releasing said ratchet from said stop bar to permit said tension device to rotate and move said carriage.

5. A typewriter carriage feeding mechanism, including a carriage construction, a

tension device, means of connection between the tension device and the carriage, a stop bar carried by said carriage construction and a reducing train of gears, a ratchet connecting said train of gears with said tension device and stop bar, whereby the tension applied to said carriage, when said carriage is permitted to move, is greater than the pressure sustained by said stop bar.

10 6. A typewriter carriage feeding mechanism, including a carriage construction, a tension device for moving said carriage, a universal bar, a stop bar carried by said carriage having a beveled member and also 15 a series of teeth, a pivoted pawl adapted to engage said teeth for checking the momentum of said carriage, a member carried by the universal bar coacting with the beveled portion of said stop bar to provide an escapement mechanism for permitting said carriage to move under the impulse of said tension device.

7. A typewriter carriage feeding mechanism, including a carriage construction, a 25 stop bar carried thereby, a universal bar, a ratchet coacting with said stop bar, and a member carried by said universal bar to provide an escapement mechanism for permitting movement of said mechanism step-by-step, and a tension device for moving 30 said carriage, said tension device consisting of a rotatable shaft, a drum carried thereby with a band connection to said carriage, a spring normally tending to rotate said shaft, 35 and means including said escapement mechanism for preventing the rotation of said shaft.

8. A typewriter carriage feeding mechanism, including a carriage construction, a 40 stop bar carried thereby, a ratchet coacting with said stop bar, a rotatable shaft, a train of gears connecting said shaft with said ratchet, a drum carried by said shaft, means for connecting said drum to said carriage 45 for pulling said carriage, a relatively adjustable drum, and a spring having one end secured to said adjustable drum and the other end secured to the shaft, for the purpose specified.

50 9. A typewriter carriage feeding mechanism, including a carriage construction, a tension device, a universal bar, a movable stop bar carried by said carriage construction, a ratchet, means of connection between said tension device and said carriage, said ratchet coacting with the stop bar and with a member carried by the universal bar to form an escapement mechanism for said tension device, said universal bar provided with

means for releasing said stop bar from said ratchet.

10. A typewriter carriage feeding mechanism, including a carriage construction, a tension device, a movable stop bar carried by said carriage construction, a ratchet coacting therewith, means of connection between said tension device and said ratchet, a universal bar provided with a member coacting with said ratchet, a stop bar comprising part of an escapement mechanism 65 for said tension device and means for overcoming the momentum of said carriage.

11. A typewriter carriage feeding mechanism, including a carriage construction, a stop bar carried thereby, a universal bar, a 75 tension device connected to said carriage, an escapement mechanism comprising a ratchet in connection with said tension device and members carried by said stop bar and universal bar, coacting with said ratchet, means 80 controlled by said escapement mechanism for momentarily causing said tension device to exert a pull on said carriage, and means for checking the momentum of said carriage. 85

12. A typewriter carriage feeding mechanism, including a carriage construction, a tension device, a pivoted stop bar carried by said carriage and having a beveled surface, a ratchet coacting with said stop bar, means 90 of connection between said tension device and said ratchet for causing the normal tension of said device to be applied to said stop bar, a band connection between said tension device and said carriage, and means for 95 momentarily releasing said ratchet from said stop bar to permit said tension device to apply a force to move said carriage longitudinally.

13. A typewriter carriage feeding mechanism, including a carriage construction, a tension device, a pivoted stop bar carried by said carriage and having a beveled surface, a ratchet coacting with said stop bar, means 100 of connection between said tension device and said ratchet for causing the normal tension of said device to be applied to said stop bar, a band connection between said tension device and said carriage, means for momentarily releasing said ratchet from said stop 105 bar to permit said tension device to apply a force to move said carriage longitudinally, and a spring-pressed pawl for checking the momentum of said carriage. 110
